SPRING CUSHION

Arthur Wesley, Chicago, and Lawrence J. Sieger,
Cicero, Ill., assignors to Burton-Dixie Corpora-
tion, Chicago, Ill., a corporation of Delaware

Application November 25, 1938, Serial No. 242,343

8 Claims. (Cl. 5—230)

The instant invention pertains to certain novel features of structure and mode of operation in bed-springs and comparable cushions, incorporating a series of upright spiral-springs.

One feature of the invention resides in a new or supplemental border-wire arrangement which is securely held in place without direct attachment to the erect spiral-springs with which it is associated.

Another principle of the invention relates to a so-called platform-top for the bed-spring or other cushion which is yieldingly secured to such auxiliary border or marginal wire referred to.

To allow those versed in, and acquainted with, this art to understand and appreciate the favorable and valuable characteristics of the present invention, a current embodiment thereof has been illustrated in detail in the accompanying drawing, and, for simplicity, like reference numerals have been employed in the several views of such drawing to designate or denote the same structural parts or mechanical elements, and from a comprehension of such construction other aims and objects of the invention will be perceived.

In this drawing—

Figure 1 is a partial plan view of a bed-spring or spring-cushion incorporating the structural features based upon the new invention;

Figure 2 is an enlarged, fragmentary, plan view of a small portion only of the bed-spring or cushion; and

Figure 3 is an edge view or elevation of that fragment of the construction shown in plan in Figure 2.

Referring to these views of the drawing, it will be readily observed that the spring-cushion or bed-spring includes a number of suitably supported, upright spiral-springs 11, 11 shown diagrammatically, arranged in longitudinal and transverse rows, the top convolution or turn of each such spring having its end knotted at 12 around the adjacent portion of the wire constituting the spring.

These springs may be of tapered or hour-glass form or of any other appropriate conformation, but they are assumed to have the knots or their equivalents at the positions indicated, particularly with reference to the marginal springs.

As is clearly portrayed in Figure 1, the top or terminal rings of these springs are connected together in any approved fashion as by intersecting or crossing helical-springs 13, 13.

A continuous border-wire 14 extends around the top margin of the structure, and, in the plane of the upper surface of the springs and such

border-wire, in a manner well-known, has spaced-apart, inner recesses or cavities receiving the outermost parts of the top convolutions or terminal rings of the marginal springs, such border-wire at its cavities being deformed or clamped at least in part inwardly around the end convolutions of the springs to hold them firmly in place, there being nothing now novel in that particular fastening means.

It is to be noted, as shown in Figure 1, that the stated knots or connections of all of the marginal springs are aligned along the sides and ends of the bed-spring or cushion so that each knot is located inwardly away from the border-wire the same distance as all other knots.

An auxiliary or secondary border-wire 15 has its ends connected together in any approved or suitable manner at 10, thus providing an endless or unbroken member which extends around the bed-spring beneath the top rings or coils thereof and just outside of the knots 12 with which they may be in contact, or out of contact, but, in any case, such supplementary border-wire 15 at each spring is wedged between its terminal-ring and the wire of the next lower convolution, as is clearly illustrated in Figure 3.

Thus such additive or subsidiary boundary-wire 15, so far as inward shifting or movement thereof is concerned, is fixed with relation to all of the marginal spiral-springs and through their top rings or coils is secured firmly to the main or principal border-wire 14.

The platform-top for the bed-spring is composed of flat-narrow, longitudinal and transverse, metal bands or straps 16 and 17, respectively, located just above and bearing on the tops of the erect spiral-springs, with their points of crossing in register with the axes of such springs.

The specified members 16 and 17 terminate short of the inner border-wire 15 and their ends are connected to such element 15 by short helical-springs 18, 18, whereby the load strains imposed on the superposed platform are transmitted to the inner border-wire 15 and through the end-rings of the spiral-springs to the outer border-wire 14.

The new and improved spring cushion or bed-spring has its platform-top yieldingly joined to the multiple border-wires and by reason of the relation of the inner border-wire to the knotted portions of the spiral-springs, it cannot be pulled inwardly by the load on the platform and such inside border-wire is assisted in performing such

function by its connection to the outer border-wire through the end-rings of the springs.

The bed-spring illustrated and described may have any type of support for the spiral-springs which seems to be desirable, but, in some cases at least, it is feasible to make the bottom and the top of the spring cushion alike or substantially identical.

This invention is presented and defined in the appended claims which should be construed or interpreted as generically as permitted by the state of the prior art and yet preserve their validity, but, it is to be remembered that the invention is not necessarily limited or restricted to the precise and exact structural details referred to because various changes and modifications may be resorted to without departure from the principles underlying the invention and without the loss or sacrifice of any material advantage incident to the employment of the invention.

We claim:

1. In a spring cushion, the combination of a group of spiral-springs with their top ends in substantially the same plane, means securing said spiral-springs together, each of the marginal spiral-springs at its top having the end of the wire forming its terminal-convolution connected to the portion of the wire next adjacent to it, said connections of the marginal spiral-springs of the cushion being in substantial alignment for each side and each end of the cushion, and a border-wire extended around the cushion below said terminal-convolutions of said marginal spiral-springs and above said next adjacent portions of the wires and just outside said connections.

2. In a spring cushion, the combination of a group of spiral-springs with their top ends in substantially the same plane, means securing said spiral-springs together, each of the marginal spiral-springs at its top having the end of the wire forming its terminal-convolution connected to the portion of the wire next adjacent to it, said connections to the marginal spiral-springs of the cushion being in substantial alignment for each side and each end of the cushion, a main border-wire extended around the cushion substantially in the plane of, and fixedly secured to

the outer portions of, the terminal-convolutions of said marginal spiral-springs, and a secondary border-wire extended around the cushion below said terminal-convolutions of said marginal spiral-springs and above said next adjacent portions of the wires and just outside said connections. 5

3. The spring cushion set forth in claim 1, in combination with a platform-top for the cushion including longitudinal and transverse flat metal bands, and means securing the ends of said bands to said border-wire. 10

4. The spring cushion set forth in claim 2, in combination with a platform-top for the cushion including longitudinal and transverse flat metal bands, and means securing the ends of said bands to said secondary border-wire. 15

5. The spring cushion set forth in claim 1 in combination with metal-bands above said spiral-springs, and means joining the ends of said bands 20 to said border-wire.

6. The spring cushion set forth in claim 2 in combination with metal-bands above said spiral-springs, and means joining the ends of said bands to said secondary border-wire. 25

7. The spring cushion set forth in claim 2 in combination with flat metal-bands above and resting on said spiral-springs, and helical-springs joining the ends of said bands to said secondary border-wire. 30

8. In a spring cushion, the combination of an assemblage of spiral-springs with their top ends in substantially the same plane, means securing said spiral-springs together, each spring of a group of marginal ones of said spiral-springs 35 having the end of the wire forming its top convolution connected to the portion of the wire next adjacent to it, said connections of said group of said marginal spiral-springs of the cushion being in substantial alignment, a border-wire section extended along said cushion below said top convolutions of said group of marginal spiral-springs and above said next adjacent portions of said wires thereof and just outside of said connections, a platform-top for said cushion, and means connecting said platform-top to said border-wire 40 section. 45
